DISPLAY DEVICE

Eldon Fox, Winchester, Ky.

Application March 10, 1950, Serial No. 148,783

3 Claims. (Cl. 40—97)

1

This invention relates to display devices and more particularly to a power operated display device for continuously exhibiting display objects, such as wallpaper or fabric samples, photographs, diagrams and documents.

It is among the objects of the invention to provide a power actuated, continuously operating display device which will present display objects, one at a time, for observation and will progressively change the objects in a predetermined order, which is of light weight and well adapted to be placed in the show window of a store or similar establishment and will operate without attention, which provides no hazard of fire or overheating and is smooth and quiet in operation, in which the display objects may be easily interchanged when desired, and which is simple and durable in construction, economical to manufacture, and not subject to malfunctioning in operation.

Other objects and advantages will become apparent from a consideration of the following description and the appended claims in conjunction with the accompanying drawings wherein:

Figure 1 is a front elevational view of a display device illustrative of the invention;

Figure 2 is a top plan view on an enlarged scale of the display device illustrated in Figure 1;

Figure 3 is an elevational view of a fragmentary portion of the device looking from the line 3—3 of Figure 2;

Figure 4 is a cross sectional view on the line 4—4 of Figure 2;

Figure 5 is an elevational view of a fragmentary portion of the device looking from the line 5—5 of Figure 2;

Figure 6 is a cross sectional view on the line 6—6 of Figure 5; and

Figure 7 is a cross sectional view on the line 7—7 of Figure 6.

With continued reference to the drawings, the display device illustrated comprises a tubular center post 10 received at one end in a hub or boss 11 extending centrally from one side of a base flange 12, the arrangement being such that when the base flange is supported on a generally horizontal supporting surface, such as a floor, the post 10 will extend vertically upward from the base flange.

A base plate 13, preferably of rectangular shape, is secured on the upper end of the post 10 and is substantially horizontal when the post is substantially vertically supported. An electric motor 14 is mounted on the base plate 13 and carries at one end a reduction gear unit 15 from which a drive shaft 16 projects substantially vertically upward.

2

An annular, preferably circular, track 17 surrounds the base plate 13 substantially coaxial with the post 10 and comprises a pair of rings of L-shaped cross section. The outer ring 18 has a bottom flange extending toward the bottom flange of the inner ring 19, and the inner ring has a bottom flange extending toward the bottom flange of the outer ring, the annular portions of the two rings being spaced apart and substantially parallel and the adjacent edges of the bottom flanges being spaced apart a distance less than the distance between the annular portions of the two opposed rings.

The inner ring 19 is supported from the base plate 13 by four arms, as indicated at 20, 21, 22 and 23 which are secured at their inner ends to the base plate 13 and project radially of the annular track to the inner track ring 19, the outer ends of these arms or spokes being rigidly secured to the inner ring by welding or other suitable means. The outer ring 18 is supported from the inner ring 19 by U-shaped brackets 24, 25 and 26 each of which has one leg secured to the inner ring and its other leg secured to the outer ring and its intermediate portion arching over the space between the annular portions of the inner and outer rings 19 and 18.

A plurality of rectangular carrier blocks 27 are carried in the space between the outer and inner rings 18 and 19 and rest on the inwardly directed bottom flanges of these rings for movement around the circular or annular track 17. A rectangular display card or plate 28 is supported from each block 27 by a connecting assembly, generally indicated at 29 and illustrated in detail in Figure 6.

Each of the connecting assemblies comprises a stem 30 extending through and secured in an aperture which extends through the corresponding block 27, the upper end of the pin or stem 30 extending above the upper surface of the block for a purpose to be presently described, and the lower end of the stem or pin extending from the lower surface of the block through the space between the bottom flanges of the outer and inner rings 18 and 19. The stem 30 is screw threaded at its lower end and a union nut 31 has a tapped hole therein which receives the screw threaded end of the stem 30 to secure the union nut on the lower end of the stem. An internally screw threaded recess 32 is provided in the lower end of the union nut 31 and a pin 33 is provided at one end with a flat, circular head 34 disposed in the recess 32 and bearing at its upper side against the inner surface of the recess. A gland nut 35 is provided with a bore extending therethrough and receiving the pin 33 and this gland nut is

threaded into the recess 32 of the union nut 31 to secure the head 34 of the pin in the recess. The pin 33 is rotatable relative to the union nut 31 and the frictional resistance to rotation of the pin 33 relative to the union nut can be varied by adjusting the gland nut 35 relative to the union nut.

At its lower end, opposite the head 34, the pin 33 is bifurcated as by having a saw cut provided diametrically therethrough, and the upper edge 10 of the corresponding display card 28 is received in the slot or saw cut provided in the lower end of the pin 33 and is secured to the pin by suitable means such as the rivets 36 which extend through registering apertures in the bifurcated end portion of the pin and in the portion of the display card 28 received in the slot of the pin. The pin 33 is secured to the display card 28 substantially at the mid-length location of the top edge of the rectangular display card so that the card is symmetrically suspended from the block 27 by the assembly 29, the display cards being movable around the circular or annular track 17 in a manner to be presently described.

A nut or hub 37 is secured on the vertical drive shaft 16 near the upper end of the latter and two arms 38 and 39 are secured at their inner ends to the hub 37 and project radially therefrom across the top of the track 17. The arms 38 and 39 are spaced apart an angular interval somewhat less than 90 degrees and each of the two arms is provided in two parts pivotally connected together at their adjoining ends, the two parts of the arm 38 being pivotally interconnected by the pivot bolt 40 and the two parts of the arm 39 being pivotally interconnected by the pivot bolt 41. These pivotal connections 40 and 41 permit the outer ends of the arms 38 and 39 to move upwardly and downwardly as the outer ends of these arms are moved around the track 17 by the motor drive shaft 16.

A first arcuately curved cam member 42 is supported on the brackets 24, 25 and 26 above the track 17 and extends from the bracket 26 past the brackets 25 and 24 to a location somewhat beyond the bracket 24. This cam member is provided at its end nearest the bracket 24 with an inclined ramp 43 and has its other end cut off substantially at right angles with the upper corner preferably rounded to a slight extent. The bracket 26 defines a position A around the track 17, and the ramp 43 defines a second position B.

A housing or casing extends across the front side of the device and has a flat wall provided with a rectangular window opening 45. The flat wall of the casing is disposed substantially perpendicular to a plane which includes the axis of post 10 and is disposed a short distance outwardly of the track 17. The window opening 45 is so located that its area is substantially vertically bisected by the plane including the axis of post 10 and disposed perpendicular to the flat wall of the casing in which the opening 45 is provided. The mid-width location of the window opening 45 constitutes a third position C around the track. A fourth operative position around the track is located substantially midway between the positions C and B and indicated at D. The two arms 38 and 39 rotate in the counterclockwise direction as indicated by the arrow on Figure 2.

A short cam member 46 is supported on the track 17 with its mid-length location at the position C on the track and is provided at each end with an inclined ramp, as indicated at 47 and 48.

The arm 38 has a length such that its outer end rides on the two cam members 42 and 46, these cam members occupying portions of a circle which is concentric with the axis of rotation of the drive shaft 16.

Assuming the hub 37 and the two arms 38 and 39 to be rotating in the direction indicated by the arrow on Figure 2, and the arm 38 to be supported at its outer end on the cam member 42 intermediate the length of this cam member, when the arm 38 reaches the end of cam member 42 at position A it will drop off of the end of the cam member and engage behind the upwardly projecting end of the pin 30 of a display card supporting assembly 29 located at position A. As the drive shaft 16 continues to rotate the arm 38 will sweep the pin 30 with the associated block 27, supporting assembly 29 and display card 28, around the track to position C at which position the cam member 47 will raise the outer end of arm 38 releasing the arm from the upper end of pin 30 and leaving the display card at position C in which it is in registry with the window opening 45.

An arcuately curved cam member 49 is disposed within the track 17 and occupies a portion of a circle concentric with the axis of rotation of the drive shaft 16. This cam member has one end provided with an inclined ramp 50 positioned between operative positions A and C on the track and has at its other end an inclined ramp 51 located at position D. Arm 39 rides on the top edge of cam member 49 and this cam member holds arm 39 out of contact with the upper ends of pins 30 as long as the arm rides on the cam member 49. Arm 38 has an upwardly projecting portion which arches over cam member 49 so that this cam member does not interfere with the operation of arm 38.

When the arm 39 rides off of the cam 49 at the ramp 50 it drops to a position at which it will engage the upper end of a pin 30 at position C. After engaging the pin at position C the arm 39 will move the pin to position D where it will ride up on the ramp 51 of the cam member 49 and leave the pin with the associated block, suspension assembly and display card at position D.

After the arm 39 has ridden up the ramp 51 and released the assembly at position D, arm 38, following arm 39, will pick up the pin at this location and move it to position B. The extent of the track from position B to position A in a counterclockwise direction is filled with blocks 27 so that when the arm 38 moves a block from position C to position B, the entire group of blocks between position B and position A, will be moved sufficiently to force another block beyond bracket 26 in a counterclockwise direction where it can be picked up by arm 38 during the succeeding rotation of the arms.

The cam members thus control the arms so that the arm 39 will pick up a block and associated elements at position C and move this block to position D. During the same rotation arm 38 will pick up a block and its associated elements at position A and move such block to position C, leaving it at position C and then picking up the first block at position D and moving it to position B where it contacts the adjacent end of the group of blocks between positions B and A, forcing another block to position A to be picked up by arm 38 during the subsequent rotation.

An arcuately curved guide member 52 is disposed within the flat wall of the casing 44 at the

top of the window opening 45 and is mounted on the casing by suitable means such as the struts or flanges 53 and 54. This guide member contacts the edges of a display card as the card is brought to position C and brings the card to a position at which it is substantially parallel to the flat wall of casing 44 and in registry with the window opening 45.

The arms will thus bring the display cards, one at a time, into registry with the window opening, leave each card for a predetermined interval in registry with the window opening, and will then subsequently move the card away from the window opening and bring a subsequent card to the window opening, the cards being moved to the window opening in a predetermined order.

In order to change the display objects it is necessary only to remove the gland nuts 35 from the union nuts 31 and substitute new assemblies including display cards, headed pins and gland nuts for those removed.

In order to dampen objectionable swinging or vibration of the cards when in position at the window opening, a strong permanent magnet 55, mounted in a sleeve 56, is secured to the outer end of a support arm 57, the inner end of which is secured to the base flange 12 with the support arm extending radially outward from the base flange. The magnet 55 is positioned directly below position C on the track 17 and a stem or armature 58 of magnetic material is secured to each display card 23 at the bottom edge of the card and depends from the card to a location closely adjacent to the upper end of the magnet. The magnetic attraction between the magnet 55 and the armatures 58 provides a damping or stabilizing force which eliminates vibration and other undesirable movements of the display cards while at the window opening.

The display cards are rectangular pieces of sheet material, preferably of an inexpensive character such as fibre board, and may be treated as dispensable elements if it is found to be more expensive to remove the display material from them than to provide new cards for new material. The display material may be mounted on one or both sides of the carrying cards or plates and, as explained above, may be of any suitable character, such as wallpaper or fabric samples, photographs, et cetera.

As the power requirements of the device are extremely small, the electric motor 14 may be a fractional horsepower motor which operates on a negligible amount of electrical energy and does not generate any important quantity of heat.

The display device may be provided with suitable illuminating apparatus, suitable lamps being preferably disposed within the casing 44 and at the opposite sides of the window opening 45 to illuminate the display objects while at the window opening.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A display device comprising a post adapted to set in substantially vertical position on a hor-

izontal supporting surface, a substantially horizontally disposed base plate secured on the upper end of said post, a motor mounted on said base plate and having a substantially vertical drive shaft, an annular track surrounding said base plate and supported from said post, a plurality of display objects suspended from said track and movable therearound, a housing spaced from said post and having a display window opening therein, curved cam members extending along said track, and two arms secured to and extending outwardly from said motor shaft to ride on said cam members, one of said arms being controlled by said cam members to move the display objects away from said display window opening to a first predetermined position along said track, and the other of said arms being controlled by said cam members to move the display objects from said first position to a second position on said track and from a third position on said track to a position in which they register with said window opening.

2. A display device comprising a support, an annular track mounted on said support, a plurality of display plates, means suspending each of said plates from said track for rotational movements about the longitudinal center lines of the plates, a motor carried by said support, arms driven around said track by said motor, cam members mounted adjacent said track and controlling said arms to move said plates, one at a time, from a first position to a second position along said track and from said second position to a third position and subsequently to a fourth position with an interval of no movement at said second position, means providing a display opening below said track at said second position, and a curved guide supported adjacent said track and above said display opening to engage said plates and bring them into alignment with said display opening.

3. A display device comprising a support, an annular track mounted on said support, a plurality of display plates, means suspending each of said plates from said track for rotational movements about the longitudinal center lines of the plates, a motor carried by said support, arms driven around said track by said motor, cam members mounted adjacent said track and controlling said arms to move said plates, one at a time, from a first position to a second position along said track and from said second position to a third position and subsequently to a fourth position with an interval of no movement at said second position, and magnetic means carried by said support and each of said display plates and operative at a location in vertical alignment with said second position to restrain said plates against movement while at said second position.
